United States Patent

Des. 242,049
Patented Oct. 26, 1976

242,049

PORTABLE DICTATION MACHINE OR THE LIKE

Eliot F. Noyes, New Canaan, Conn., assignor to
International Business Machines Corporation

Filed Mar. 17, 1975, Ser. No. 559,300

Term of patent 14 years

Int. Cl. D14—01

U.S. Cl. D26—14 B

FIG. 1

FIG. 2

FIG. 1 is a front perspective view of a portable dictation machine or the like showing my new design; and
FIG. 2 is a rear perspective view thereof.

I claim:

The ornamental design for a portable dictation machine or the like, substantially as shown.
